UNITED STATES PATENT OFFICE

92,820

DESIGN FOR COMBINED MOLDED ICE CREAM AND CONTAINER THEREFOR

Elmer J. Mather, Chevy Chase, Md.

Application March 21, 1934, Serial No. 51,125

Term of patent 14 years

To all whom it may concern:

Be it known that I, ELMER J. MATHER, a citizen of the United States of America, and a resident of Chevy Chase, Maryland, have invented a new, original, and ornamental Design for Combined Molded Ice Cream and Container Therefor, of which the following is a specification, reference being had to the accompanying drawing, forming part thereof, in which drawing Fig. 1 is a per-

spective view and Fig. 2 is a front view of combined molded ice cream and container therefor embodying my new design.

I claim:

The ornamental design for combined molded ice cream and container therefor, as shown.

In testimony whereof I have signed this specification.

ELMER J. MATHER.
